(57) **CLAIM**

The ornamental design for a sensor transmitter for measuring air pressure of a tire, as shown and described.

DESCRIPTION

FIG. 1 is a front perspective view of a sensor transmitter for measuring air pressure of a tire showing my new design; FIG. 2 is a back perspective view thereof; FIG. 3 is a front view thereof; FIG. 4 is a back view thereof; FIG. 5 is a top view thereof; FIG. 6 is a right side view thereof; FIG. 7 is a left side view thereof; FIG. 8 is a bottom view thereof; FIG. 9 is a partially enlarged front perspective view thereof; FIG. 10 is a partially enlarged back perspective view thereof; and, FIG. 11 is a partially enlarged front view thereof. The broken lines shown are included for the purpose of illustrating portions of the sensor transmitter for measuring air pressure of a tire and form no part of the claimed design.
